Primary Examiner — Elizabeth Albert*Assistant Examiner* — Kelley Donnelly(74) *Attorney, Agent, or Firm* — Fay Sharpe LLP(57) **CLAIM**

The ornamental design for a front wall of a cabinet shelf, as shown and described.

DESCRIPTION

FIG. 1 is a top rear perspective view of a front wall of a cabinet shelf;

FIG. 2 is a top plan view thereof;

FIG. 3 is a rear elevational view thereof;

FIG. 4 is a bottom plan view thereof;

FIG. 5 is a front elevational view thereof; and,

FIG. 6 is a right side elevation view thereof, with a left side elevation view being a mirror image thereof.

The dashed broken lines in FIGS. 1-6 represent environmental subject matter and form no part of the claimed design.
